POSITIONING MEANS FOR BOX PARTS

Edward M. Floreycy, Rockaway, N. J., assignor to
Stapling Machines Co., a corporation of Delaware

Application January 25, 1936, Serial No. 60,789

8 Claims. (Cl. 1—8.2)

This invention relates to machines for making wirebound box blanks.

It is an object of the invention to provide improved means for relatively positioning the box parts as they pass through the machine.

It is a further object of the invention to provide means for positioning sheets of box side material in overlapping relationship prior to and during a fastening operation.

10 In the drawings:—

Figure 1 is a perspective view of one type of wirebound box blank which the machine of this invention is adapted to produce.

Fig. 2 is a perspective view of another type of wirebound box blank which the machine of this invention is adapted to produce.

Fig. 3 is a side elevation of a wirebound box blank machine in which the invention may be embodied.

20 Fig. 4 is an enlarged perspective view of one of the sheet-positioning devices of this invention.

Fig. 5 is an enlarged perspective view of a portion of the work-conveying chains of the machine and showing the manner in which two sheets of side material are positioned in overlapping relationship.

Fig. 6 is an enlarged side elevation of one of the work-conveying chains with materials for 30 one type of box blank shown thereon and showing one of the sheet-positioning devices in its normal raised position.

Fig. 7 is a similar view but showing the position of the parts when the positioning device is lowered during a stapling operation.

Fig. 8 is similar to Fig. 6 but shows a different type of box blank being operated upon.

Fig. 9 is similar to Fig. 7 but shows the type of box blank which is disclosed in Fig. 8.

40 One type of wirebound box blank is shown in Fig. 1 consisting of four sections of cleats 1 and side sheets 2 and 3 connected together in foldable relationship by flexible binders (preferably wires) 4 stapled to the sheets and cleats. In the blank shown in Fig. 1, the sheet 3 of each section overlaps the sheet 2, as shown. This overlapping relationship of the sheets is desirable for the shipment of certain commodities.

50 Fig. 2 discloses a different type of wirebound box blank which may be made on the machine. It consists of cleats 1 and an integral sheet of side material 5 preferably of fiberboard or the like which may be bent at potential box corners when the blank is folded into box form. Un-

derlying the sheet 5 at each potential box corner is a strip of bendable material (preferably fiberboard) 6. The strips 6 are incorporated to strengthen the completed box at and adjacent the corner edges. Stapled to the sheet 5, the strips 6, and the cleats 1, are flexible binders (preferably wires) 7.

Referring to Fig. 3, the cleats and sheets for a box blank are positioned on endless conveyor chains 8 which carry the material beneath stapling mechanism 9 which staples the box parts together and the binding wires thereto. In said figure, the materials are fed to the stapling mechanism 9 in the direction indicated by the arrow. As the materials approach the stapling mechanism 9 they pass under presser bars 10 which press the box parts firmly into position on the conveyor chains during a stapling operation.

Referring to Fig. 5, each conveyor chain is channel-shaped to receive the cleats 1. The cleats 1 are positioned endwise by fins 11 extending from blocks 12 adjustably secured to a flange 13 of the chains 8. The rear edge of overlapping sheet 3 is positioned by fins 14 carried by blocks 12. The ends of the side sheets are held against lateral movement by outer flanges 15 of the chains 8.

Because the sheets of side material sometimes warp, the fins 14 extend above the true surface level of the sheet to insure engagement with the rear edge of the sheet regardless of its warped condition. Similar upwardly extending fins or fingers must be provided to contact and position the rear edge of the under or overlapped sheet 2. Such means, however, necessarily lies beneath upper sheet 3 and therefore holds it in the raised position shown in Fig. 6 and out of contact with under sheet 2. During the feed of the box parts to the stapling mechanism 9 the upper sheet 3 need not contact with the lower sheet 2, but when the two sheets are stapled together it is necessary for them to be in contact with each other. Therefore, provision is made to lower the positioning fin or finger for the under sheet 2 during the time the sheets 2 and 3 are being stapled together.

The device for accomplishing this result is best shown in Fig. 4. It consists of a block 16 which may be adjustably secured to a flange 17 of chains 8 by means of set screws 18. The block 16 carries an upwardly extending positioning finger 19 which is mounted to slide vertically in the block 16.

As best shown in Fig. 6, finger 19 is normally

held in its raised position by a coil spring 20. The spring 20 is strong enough to hold the finger 19 in raised position under the weight of upper sheet 3, as shown in Fig. 6, but yields under additional pressure to the position shown in Fig. 7, thus permitting upper sheet 3 to contact lower sheet 2.

The pressure for lowering the finger 19 may be applied by the presser bars 10 as the materials are fed beneath it, or by the thrust of the stapling mechanism when it drives a staple through the upper sheet 3 and the lower sheet 2 and into the cleat 1.

Figs. 6 and 7 illustrate the action of the positioning finger 19 when blanks of the type shown in Fig. 1 are being operated upon, and Figs. 8 and 9 illustrate the manner in which the positioning finger 19 operates to position the strips 6 beneath the sheet 5 when the type of blank shown in Fig. 2 is being operated upon.

The mechanism for feeding the conveyor chains 8 and for forming and driving staples need not be described herein, as such mechanisms are well known, being shown, for example, in patent to Thompson No. 1,738,806 of December 10, 1929, reference to which is hereby made for a detailed description of such mechanisms.

It will be understood that the invention is not to be limited to the specific embodiment shown for purposes of illustration as it may be variously embodied without departing from the invention.

It will also be understood that all of the inventive features need not be used conjointly as 35 they may be used to advantage in various combinations as defined in the sub-joined claims.

I claim:

1. In a machine of the character described, the combination of fastener setting mechanism 40 and means to feed thereto sheets of side material in overlapping relationship including a vertically slidable positioning finger to engage the overlapped edge of the under sheet, said finger being longer than the thickness of the side 45 sheet to extend above the true surface level of said sheet and contact the under side of the overlapping upper sheet, spring means normally holding the finger in raised position, and means acting through pressure on the upper sheet to lower the finger to the surface level of the under sheet when the upper sheet is being fastened to the under sheet.

2. In a machine of the character described, the combination of fastener setting mechanism 55 and means to feed thereto sheets of side material in overlapping relationship including a vertically slidable positioning finger to engage the overlapped edge of the under sheet, said finger being longer than the thickness of said sheet 60 to extend above the true surface level of said sheet and contact the under side of the overlapping upper sheet, means normally holding the finger in raised position, and means acting through pressure on the upper sheet to lower the finger to the surface level of the under sheet when the upper sheet is being fastened to the under sheet.

3. In a machine of the character described, the combination of fastener setting mechanism and means to feed thereto sheets of side material in overlapping relationship including a vertically slidable positioning finger to engage the overlapped edge of the under sheet, said finger being longer than the thickness of said sheet to extend above the true surface level of said sheet and contact the under side of the overlapping upper sheet, and means yieldingly to hold 10 the finger in raised position whereby pressure on the upper sheet during a fastening operation will force the finger down to the surface level of the lower sheet and permit the upper sheet to contact the lower sheet while the two sheets 15 are being fastened together.

4. In a machine of the character described, the combination of fastener setting mechanism and means to feed thereto sheets of side material in overlapping relationship including a positioning member adapted to underlie the upper sheet and to engage the rear edge of the lower sheet and to extend above the true surface level of the under sheet, and means acting through pressure on the upper sheet to lower the positioning 25 member during a stapling operation.

5. In a machine of the character described, the combination of fastener setting mechanism and means to feed thereto sheets of side material in overlapping relationship including a vertically 30 movable positioning member constructed and arranged to underlie and support the upper sheet and to engage the rear edge of the lower sheet, said member being yieldingly held in raised position whereby pressure on the upper sheet during a fastening operation will lower the finger and permit the upper sheet to contact the lower sheet.

6. In a machine of the character described, the combination of fastener setting mechanism and 40 means to feed a box part thereto including a vertically movable member to engage the rear edge of the box part, means normally holding it in raised position, and means acting through pressure on a box part to lower the member 45 and hold it in lowered position during a fastener setting operation.

7. In a machine of the character described, the combination of fastener setting mechanism and means to feed a box part thereto including a vertically movable member to engage the rear edge of the box part, means yieldingly holding it in raised position, and means acting through pressure on a box part to lower the member and hold it in lowered position during a fastener setting operation.

8. In a machine of the character described, the combination of fastener setting mechanism and means to feed a box part thereto including a vertically movable member to engage the rear 60 edge of the box part, means acting through pressure on a box part to lower the member as it approaches the fastener setting mechanism, and means to raise the member after it passes the fastener setting mechanism.

EDWARD M. FLORCYK.
